UNITED STATES PATENT OFFICE.

JOHN AMMEN BLAKE, OF GREENWOOD, SOUTH CAROLINA.

SURGICAL SUTURING INSTRUMENT.

Application filed September 1, 1926. Serial No. 133,054.

This invention relates to surgical instruments, particularly to suturing devices, and has for its object the provision of a novel instrument by means of which stitches or sutures of any suitable flexible material may be made in or applied to a wound or incision.

An important object of the invention is to provide an instrument of this character so constructed and arranged that it may 10 be used for applying a series of stitches or sutures at equally spaced points, or individually placed stitches which may be the same or variable distances apart as preferred.

Another object is to provide an instrument of this character embodying needles and handle means so connected therewith as to be capable of operation in a step-like manner so that during the operation of taking one stitch one needle will overlap the 20 other while at the next successive operation it will underlie the same, the alternate or step-like action producing a series of uniform stitches at the same distance apart.

A further object of the invention is the 25 provision of an instrument of this character in which the construction and arrangement of parts are such that only the initial stitch will extend across the outside of the incision or wound in visible position, all the subsequent stitches being concealed except at the ends where the looping, automatic or manual, of the successive stitches is effected, the interlooping being automatic or manual 30 dependent upon the selected manner in which the instrument is used.

A still further object of the invention is to provide a suturing device provided with 40 adjustable tension means for whatever flexible material is used such as wire, gut or silk.

Another object is to provide an instrument 45 of this type having detachable needles of different varieties capable of selective employment depending upon the nature of the stitch desired.

An additional object is to provide a suturing 50 instrument which will be comparatively simple and inexpensive to manufacture, easy to use, rapid in action, efficient and durable in service, and a general improvement in the art.

With the above and other objects and advantages in view, the invention preferably 55 consists in the arrangement and combination of parts and detailed structural features to be hereinafter more fully described

and claimed, and illustrated in the accompanying drawings in which:—

Figure 1 is a front elevation of the instrument showing it in normal position and equipped with the needles for effecting the 60 staggered or off-center stitching.

Figure 2 is an edge elevation.

Figure 3 is a plan view or elevation looking at the needles.

Figure 4 is a detail sectional view through 65 the pivot joint showing the intermediate position of the parts for off-center stitching.

Figure 5 is a similar view showing the pivot element in position within the throat or slot preparatory to arranging the parts 70 for on-center stitching.

Figure 6 is a view similar to Figure 5 with the pivot in the lateral slot ready for on-center stitching.

Figure 7 is a detail section through a 75 portion of one handle member showing the detachable mounting of the needle therein.

Figure 8 is a section taken at right angles to Figure 7.

Figure 9 is a fragmentary side elevation 80 showing the tension device.

Figure 10 is a perspective view of the tension plate removed.

Figure 11 is a cross section taken on the line 11—11 of Figure 4. 85

Figure 12 is a side elevation of a portion of the instrument showing the position of the needles for starting a suture.

Figures 13, 14, 15 and 16 are similar views 90 showing successive steps in off-center stitching.

Figure 17 is a view showing an incision as stitched by the instrument, the stitches being of course greatly exaggerated for the sake of clearness. 95

Figures 18, 19 and 20 are fragmentary views showing the type of needles employed for on-center stitching, the three views illustrating successive steps.

Figure 21 is an elevation of a wound or 100 incision stitched by the on-center method.

Figure 22 is a longitudinal section through one of the needles for effecting the off-center stitching, and

Figure 23 is a detail section through the 105 end portion thereof.

Referring more particularly to the drawings, I have shown the device as comprising a pair of blades or handle members 1 and 2 which are somewhat similar in construction 110

and of the same general contour except that the former is shown as provided with a loop 3 constituting a thumb hold whereas the latter is provided with two loops 4 and 5 for the forefinger and remaining fingers respectively. The members 1 and 2 are both formed with similar extensions 6 which diverge and each of which is formed with a socket 7 into which leads a hole 8 for a purpose to be described.

The members 1 and 2 are pivotally connected by a peculiar joint which permits the members to pivot for simple relative rotary movement in opposite directions or for relative rotary or rocking movement on different axes, depending upon the nature of the stitch or suture desired, this depending, in its turn, upon the character of the wound or incision. In the present instance, the pivot means is shown as comprising a pivot member 9 having a squared or other angular portion 10 stationarily mounted through the member 2. Obviously this member may be welded, brazed or otherwise permanently fastened or it may be provided at one end with a head 11 for the purpose of preventing longitudinal displacement in one direction. Where the member 9 passes through the member 1, it is formed with a cylindrical portion 12 which extends for a distance preferably substantially one-half the thickness of the member 1, the remaining portion being cut away at opposite sides as at 13 to define a constricted neck 14 terminating in a head 15 located against the outer side of the member 1 for preventing longitudinal displacement of the member 9 in the other direction. Clearly, this pivot member 9 is necessarily formed of at least two parts which are rigidly secured together after assembling with respect to the blade or handle members 1 and 2. The member 1 is shown as formed with a longitudinally extending slot 16 of at least the same width as the diameter of the cylindrical portion 12 of the pivot member, and located at one side of the slot 16 is a lateral opening 17 of substantially the same width as the cylindrical portion 12. A portion of this opening leads directly into the slot 16 whereas the remaining portion registers with a circular hole 18 which communicates with the slot 16 through a constricted throat 19. Clearly, when the handle members are in their normal position, as shown in Figures 1 and 4 the cylindrical portion 12 of the pivot member is located within the longitudinal slot 16 so that the handle members 1 and 2 may be moved relatively in a longitudinal direction simultaneously with or prior to pivoting. By swinging the handle members 1 and 2 with respect to each other they may be brought into the position shown in Figure 5 so that the constricted neck portion 14 of the pivot may be passed through the throat

19 and brought into the circular hole 18, as shown in Figure 6, in which position of the parts the handle members 1 and 2 will have their movement limited to rocking or turning about a common axis. The reason for these different positions will be hereinafter explained and it is an important feature of the invention.

For holding the blade or handle members 1 and 2 in normal position and for returning them to normal or spread position after the grips have been squeezed together during the taking of a stitch as will be described, I preferably provide a leaf spring 20 located between the members 1 and 2 and secured at one end to one, the other end having a slot 21 therein detachably engaged upon a pin 22 projecting from the other handle member. When it is desired to change the pivot 9 from engagement within the slot 16 to engagement within the hole 18, or vice versa, it is of course necessary that the slotted end of the spring 20 be disengaged from the pin 22 so that the handle members may be moved relatively to the necessary extent for permitting manipulation to shift the pivot.

It is possible to use needles of two types, as will be explained, one type being designated by the numeral 23 and the other by the numeral 24. Only the former are shown in detail for the reason that both varieties possess the same general characteristics in point of mounting, etc. The needles 23 are represented as of identical construction and each is formed into a curved or hook-shaped body 25 flat on their inner, abutting faces and rounded on their outer faces and terminating in a sharp point 26 adapted to be penetratingly engaged through the edges A of a wound or incision B. Each needle is formed with a longitudinal passage 27 which opens out at one end to the side through a hole 28 located some distance back of the point. The other end of the passage leads out to the outer edge of the needle through a flaring opening 29 in overlapping relation to which is arranged a tension device for the wide, gut, silk or other material to be used for suturing. It is intended that such flexible material, indicated at 30, be used in the form of a single strand which may initially be cut to the proper length for sewing or stitching the particular wound or incision in question. This flexible member is passed through the passages 27 in both needles and extends across the points thereof, the ends being left free as indicated in Figures 1 and 2.

For preventing accidental shifting of the flexible material, I provide a tensioning device 31 which in the present instance is shown as consisting of an angular plate 32 having a tapered opening 33 therein adapted to be brought more or less into registration

with the flaring opening 29 in the needle, the other wing 34 of the tension device having an elongated slot 35 therein through which passes a screw 36 threaded into the needle and provided for the purpose of maintaining the angular plate at a desired adjusted position so that the narrower end of the opening 33 may be brought into more or less compressing or frictional engagement 10 with the flexible material. Each needle is shown as having such a tensioning device. Clearly, some other structure of an equivalent nature may be provided for this purpose there being no particular limitation in this 15 respect.

The means for holding the needles in association with the blade or handle members 1 and 2 is here shown as comprising reduced extensions 37 formed integrally upon the needles and slidably engaged within the sockets 7, each extension being cut away at one side as shown at 38 to accommodate or permit inward movement of a leaf spring 39 which is anchored to the extension at one end as shown at 40 and which has its other end carrying a pin 41 engageable within the hole 8. This connection will hold the needles firmly with respect to the blade or handle members while at the same time in case it is desired to remove the needles it is easily accomplished provided some pointed implement be inserted through the holes 8 to effect disengagement of the pins 41 therefrom. Clearly, an equivalent mounting may be provided within the spirit of the invention.

The needle members 24 may be constructed identically the same manner as the needles 23 except that they are of such curved shape that the points thereof are arranged in end to end relation instead of being overlapped as is the case with the needles 23.

In the operation, let it be first assumed that it is desired to sew up the wound or incision B with a series of automatically interlinked stitches, or by means of the off-center method. In such an event, the pivot member 9 is arranged to be located entirely within the slot 16, as shown in Figure 4. With, say, the handle member 1 moved longitudinally with respect to the handle member 2 to bring the pivot at the lower end of the slot 16, the point of the needle carried by the member 2 is forced through the edges of the incision as shown in Figure 12, the flexible material 30 being drawn through the edges and forming a loop 42, that portion 43 of the flexible material which initially bridged the needles being brought across the incision as shown. The operator of course holds the device in one hand with his thumb extending through the loop 3, his forefinger through the loop 4 and his remaining fingers through the loop 5 so that the device may be manipulated in a manner similar to scissors or

pliers. When the handle members are then 65 squeezed together, it is intended that prior thereto, or simultaneously therewith, the handle member 1 be moved downwardly so that the pivot 9 will approach the other end of the slot 16, the intermediate position being shown in Figure 13 and the final position in Figure 14. As the handle members are brought together and moved relatively in a longitudinal direction, the point of the other needle, the one carried by the handle 70 1, is engaged through the loop 42, dragging it down to the position shown in Figure 15, and at the end of the relative longitudinal movement of the members 1 and 2 this needle is forced through the edges of the incision, 75 as shown in Figure 15, the needle carrying the thread therein through the skin or flesh. This results in anchoring the stretch 43 of the flexible material which initially bridged the needles. This also forms a loop 44 80 at the opposite side of the incision from that where the loop 42 is located. The handle members 1 and 2 are then slid longitudinally relatively in the opposite direction to bring the needle carried by the handle 2 to a point 85 below the other needle, the point of the needle engaging within the loop 44 and dragging it down, as shown in Figure 16. This needle is then forced through the incision to the opposite side, to form the next loop in which the 90 needle carried by the handle 1 is engaged in a similar manner. This step by step movement is continued until the wound or incision is fully stitched or sewed as shown in Figure 17 which discloses an exaggeration of the 95 inner engaging loops, for the sake of clearness. It will be seen that only the portion or stretch 43 of the flexible material extends across the outside of the incision, all of the other stitches or sutures extending through 100 the same.

In case the needles 24 are used, the spring 20 is disengaged from the pin 22 and the handle members 1 and 2 manipulated to bring the pivot member 9 into the circular hole 18 so that the needles will be held in end to end relation while the handles are swung upon a single axis instead of being moved longitudinally as well, as above described. In stitching with these needles, they are first arranged in spaced relation at opposite sides of the incision, as shown in Figure 18, the portion 45 of the flexible material bridging the needles, extending across the outside of the incision. The operator then squeezes the handles together to force the needles through the edges of the incision and they, being concentrically formed, will glide over each other to form a single passageway or puncture, as shown in Figure 19. 120 This forms loops 46 through which the operator then inserts the arms 47 of a spreader 125 48 for holding these loops while the needles

are withdrawn and the instrument moved to a new position along the incision. Upon reaching this new position, the needles are engaged through the loops 46 and forced 5 through the edges of the incision. This operation is repeated until the desired number of stitches have been taken.

From the foregoing description and a study of the drawings, it will be apparent 10 that I have thus provided a simply constructed instrument which will be very convenient to use not only on account of the rapidity of the action but also on account of the neatness and uniformity of the stitching. 15 It is really believed that the construction, operation and advantages will be readily apparent to one skilled in the art without further explanation.

The improved suturing device is admirably 20 adapted for either internal suturing, such as is sometimes necessary in abdominal operations or the like, or in external suturing of wounds, or incisions. As has been stated either of these operations may be performed 25 with the device arranged for what has been termed off-center suturing, that is, with the pivot arranged in the slot and the needles alternating in their movements. When the wound or incision has been sewed or sutured 30 in the manner described and with only the single, initial strand of the suture exposed, the edges A are forced inwardly by the bandages which are applied afterwards so that they lie in edge to edge relation, and the 35 stitches are consequently stretched taut with the result that such relation is maintained throughout the healing period and a much cleaner, smoother, single-line scar is the result, without the usual unsightly roughness caused by the ordinary over and over stitching. 40 The long loops at the sides of the scar may also be readily severed when the proper period arrives for the stitches to be removed.

The form of stitching referred to as on-center stitching, where the pivot remains stationary and the concentric needles are employed, is used solely for external sewing, because of the use of the loop-holding device in the form of the two-pronged fork, at a certain stage in the operation of suturing 50 in this manner.

It will be further seen that the operating surgeon in manipulating this single handed instrument, either in the on-center or the off-center method of using the same, has the use of his other hand to hold the edges of the wound or incision together or to apply and detach the loop-holding fork, thus eliminating the necessity of an assistant surgeon to 60 perform such functions.

While I have shown and described a preferred embodiment of the invention, it should be understood that I reserve the right to make such changes in the form, construction 65 and arrangement of parts as will not depart

from the spirit of the invention or the scope of the subjoined claims.

What is claimed is:—

1. In an instrument of the character described, a pair of handle members pivoted in crossed relation and terminating in finger grips, and needles carried by the handle members adapted to operate in overlapping relation, each needle having a longitudinal passage therethrough opening out at one side in spaced relation to the end and opening out at its other end adjacent the handle member. 70

2. In an instrument of the character described, a pair of handle members pivoted in crossed relation and terminating in finger grips, and needles carried by the handle members adapted to operate in overlapping relation, each needle having a longitudinal passage therethrough opening out at one side in spaced relation to the end and opening out at its other end adjacent the handle member, said passage being adapted for the passage of flexible suturing material, and means located at the second named opening for applying tension to the suturing material. 80

3. In an instrument of the character described, a pair of handle members pivoted in crossed relation and terminating in finger grips, and needles carried by the handle members adapted to operate in overlapping relation, each needle having a longitudinal passage therethrough opening out at one side in spaced relation to the end and opening out at its other end adjacent the handle member, the passage being for the feed of suturing material, and an adjustable plate member mounted adjacent each second-named opening and apertured for the passage of the suturing material, the plate member being adjustable to regulate the position of the aperture therein with respect to the second-named opening. 95

4. In an instrument of the character described, a pair of handle members pivoted in crossed relation and terminating in finger grips, and needles carried by the handle members adapted to operate in overlapping relation, each needle having a longitudinal passage therethrough opening out at one side in spaced relation to the end and opening out at its other end adjacent the handle member, the passage being for the accommodation of suturing material, and tension means for the material comprising an angular plate member carried by each needle at the second named opening and having an aperture adapted to register to a greater or less extent with the second named opening, and means for adjusting the position of the angular plate. 110

5. In an instrument of the character described, a pair of handle members pivoted in crossed relation and terminating at one end in grips, the other ends of the handle 120

members diverging and being formed with sockets, needle members carried by the handle members and having reduced extensions engaged within said sockets, and latch means for retaining the extensions within the sockets.

6. In an instrument of the character described, a pair of handle members pivoted in crossed relation and terminating at one end in grips, the other ends of the handle members diverging and being formed with sockets, needle members carried by the handle members and having reduced extensions engaged within said sockets, each extension being cut away at one side, a leaf spring secured at each cut away portion and carrying a pin, the handle member having a hole communicating with the socket for the reception of said pin.

20 7. In an instrument of the character described, a pair of handle members arranged in crossed relation, needles carried by the handle members, and means pivotally and slidably connecting the handle members whereby the needles may be caused to move in different arcuate paths.

8. In an instrument of the character described, a pair of handle members carrying needles, means pivotally connecting said members and selectively confining them to movement about a common axis and permitting relative sliding movement irrespective of the pivoting.

35 9. In an instrument of the character described, a pair of handle members carrying needles, means pivotally connecting the members, and means permitting shifting of the pivot point.

10. In an instrument of the character described, a pair of handle members carrying needles, means pivotally connecting the members, and means permitting selective shifting of the pivot point, when the handles are in predetermined positions.

45 11. In an instrument of the character described, a pair of handle members carrying needles, means pivotally connecting the members, means permitting manual shifting of

the pivot point, and means for preventing the accidental shifting of the pivot point.

50 12. In an instrument of the character described, a pair of pivoted handle members arranged in crossed relation and carrying needles, one of said members having a longitudinal slot receiving the pivot for permitting longitudinal movement of the members relative to each other.

55 13. In an instrument of the character described, a pair of handle members arranged in crossed relation, needles carried by the handle members, a pivot member carried by one handle member, the other handle member having a longitudinal slot and a transverse opening communicating therewith, the pivot member being selectively engageable within said slot or said opening.

60 14. In an instrument of the character described, a pair of handle members arranged in crossed relation, needles carried by the handle members, a pivot member carried by one handle member, the other handle member having a longitudinal slot and a transverse opening communicating therewith, the pivot member being selectively engageable within said slot or said opening, and means for retaining the pivot member in the opening.

65 15. In an instrument of the character described, a pair of handle members arranged in crossed relation, needles carried by the handle members, a pivot carried by one handle member at the point of crossing, the pivot having a cylindrical extending portion and a constricted neck portion, the other handle member having a longitudinal slot slidably engaged upon said cylindrical extending portion and having a lateral opening communicating with the slot through a constricted throat, the handle members being relatively movable to pass said constricted neck portion through the throat into said lateral opening.

70 In testimony, that I claim the foregoing as my own, I have hereto affixed my signature.

JOHN AMMEN BLAKE.
